Inventor:
William E. Paul,
by *Charles E. Muller*
His Attorney.

UNITED STATES PATENT OFFICE.

WILLIAM E. PAUL, OF SCHENECTADY, NEW YORK, ASSIGNOR TO GENERAL ELECTRIC COMPANY, A CORPORATION OF NEW YORK.

TRANSFORMER.

Application filed February 9, 1928. Serial No. 253,173.

My invention relates to transformers and more particularly to high voltage transformers of small capacity and adapted to be used where high accuracy is not essential. Trans-
5 formers of this character may be used satisfactorily to operate relays for instance. A good inductive coupling between the two windings of a transformer requires that they be close together so that the leakage flux may
10 not be excessive. It is difficult to place the windings close together, however, if the voltage between them is very high because there must be sufficient insulation between them to withstand the high voltage. The general ob-
15 ject of the invention is to provide an im-
proved transformer construction in which the windings may be reasonably close together even though the difference between their volt-
ages may be very high.
20 The invention will be better understood from the following description taken in connection with the accompanying drawing in which Fig. 1 is a sectional view of a trans-
former constructed in accordance with the
25 invention and Fig. 2 is a similar view of a modified form of the invention.
Like reference characters refer to similar parts in both figures of the drawing.
In the form of transformer shown in Fig.
30 1, the primary winding 10 surrounds a mag-
netic core 11 and is connected by conductors
12 and 13 to the two primary terminals 14
and 15. The winding 10 and its core 11 are
35 enclosed in a closed casing 16 of insulating
material such as glass which is highly evac-
uated. This casing is of elongated form with
the winding 10 and core 11 midway between
its two ends. A secondary winding 17 on
40 a spool 18 surrounds the central portion of
the casing 16 so that this secondary winding
also surrounds the primary winding 10 and
core 11. This construction brings the two
windings reasonably close together so that the
45 magnetic coupling between them will be satis-
factory. The secondary winding 17 is sur-
rounded by a layer of magnetic material 19
which may comprise a plurality of magnetic
rods or wires laid parallel to the axis of the
50 two windings 10 and 17 to provide a return
path for the magnetic flux in the core 11.
This magnetic layer 19 may be held in place
by an outer insulating covering 20. The two
end portions of the casing 16 are long enough
55 to prevent arc over between the terminals 14
and 15 and the secondary winding 17. The
end portions of the casing 16 may also be
corrugated as shown to increase the surface
leakage paths between the secondary wind-
ing and the terminals.
60 Ordinary dry air at atmospheric pressure
is of course a very good insulator. As the
pressure is decreased, the dielectric strength
of the air decreases at first but finally it be-
gins to increase and as the pressure becomes
65 very small the dielectric strength becomes
exceedingly high and it is now possible to ob-
tain such low pressure and such high vacu-
ums that their insulating properties are
almost perfect. The vacuum in the casing 16
70 is preferably of this order and at least so high
as to provide substantially better insulation
between the two windings 10 and 17 than
would be provided by air at atmospheric
pressure or by insulating materials such as
75 are commonly used in transformer construc-
tion. The primary winding 10 and core 11
are suspended in the casing by the conductors
12 and 13 and out of contact with the sides of
the casing so that they are completely sepa-
80 rated and insulated from the casing walls
by a region of high vacuum. The electrical
and magnetic losses in the primary winding
and core appear as heat which cannot of
course be dissipated to any substantial extent
85 through the vacuum but this heat may flow
through the conductors 12 and 13 to the ter-
minals 14 and 15 which may be provided with
heat conductive discs 21 to increase the rate
of dissipation of this heat.
90 In the form of the invention shown in
Fig. 2, the primary winding 10 surrounds the
core 11 and both winding and core are sur-
rounded by an elongated casing or tube 16 of
insulating material such as glass. The tube
95 16 comprises two concentric spaced walls with
the space between them highly evacuated,
the ends of the two walls being sealed to-
gether to maintain the vacuum. The second-
ary winding 17 on a spool 18 surrounds the
100 central portion of the tube 16 so that it also
surrounds the primary winding 10 and core
11. Magnetic members 19 span the secondary
winding 17 to provide return paths for the
magnetic flux in the core 11. The vacuum
105 between the walls of the tube 16 is interposed
between the secondary winding and the pri-
mary winding and core. The primary wind-
ing and its core in the arrangement shown in

Fig. 2 may be easily cooled by a current of some cooling medium such as air through the tube 16.

In both forms of the invention which have been described, a region of high vacuum is interposed between the primary winding 10 which may be at very high voltage and the secondary winding 17 which may be at a very much lower voltage. The highly efficient insulation provided by the vacuum makes it practicable to arrange the windings substantially closer together than is the case with ordinary insulation such as has been heretofore used for this purpose, the result being generally better operating characteristics such as lower reactance and more uniform voltage ratio as the load on the transformer is varied.

The invention has been explained by describing and illustrating certain embodiments thereof but it will be apparent that various changes may be made without departing from the scope of the invention as defined in the appended claims.

What I claim as new and desire to secure by Letters Patent of the United States, is:

1. A transformer including a primary winding, a closed casing having a high vacuum surrounding said winding, and a secondary winding surrounding said casing and primary winding.

2. A transformer including a magnetic core, a primary winding surrounding said core, a secondary winding surrounding said primary winding and core and means providing an insulating region of high vacuum between said secondary winding and said primary winding and core.

3. A transformer including a magnetic core, a primary winding surrounding said core, a highly evacuated casing surrounding said primary winding and core, a secondary winding surrounding said casing, and magnetic means providing a return path for magnetic flux outside said secondary winding.

In witness whereof, I have hereunto set my hand this 8th day of February, 1928.

WILLIAM E. PAUL.
